PERCIVAL W. JONES, OF LAKEWOOD, RHODE ISLAND, ASSIGNOR TO E. KIRSTEIN SONS CO., OF ROCHESTER, NEW YORK, A CORPORATION OF NEW YORK.

EYEGLASS-MOUNTING.

1,204,449.

Specification of Letters Patent. Patented Nov. 14, 1916.

Application filed June 14, 1916. Serial No. 103,640.

To all whom it may concern:

Be it known that I, PERCIVAL W. JONES, of Lakewood, in the county of Kent and State of Rhode Island, have invented certain new and useful Improvements in Eye-glass-Mountings; and I do hereby declare the following to be a full, clear, and exact description of the same, reference being had to the accompanying drawings, forming a part of this specification, and to the reference numerals marked thereon.

My present invention relates to eyeglasses and more particularly to eyeglasses of the finger-piece type, and it has for its object to provide a simple, durable and attractive mounting that will offer certain conveniences in manipulation both during manufacture and when in use.

The improvements are directed in part toward making both the guard lever and the actuating spring therefor easily detachable. While the guard lever may be removed without first removing a pivot screw, or other corresponding part, it is nevertheless less securely held in place while in its operative position and can be detached only when rotated to another definite position that it cannot occupy while the eyeglasses are clinging to the nose.

To these and other ends the invention resides in certain improvements and combinations of parts all as will be hereinafter more fully described, the novel features being pointed out in the claims at the end of the specification.

In the drawings: Figure 1 is a top plan view much enlarged of one side of any eyeglass mounting constructed in accordance with and illustrating one embodiment of my invention, the guard or nose pad being shown in horizontal section; Fig. 2 is a bottom plan view with the nose pad removed; Fig. 3 is a side elevation taken from the inner or bridge side of the mechanism, the bridge being shown broken away; Fig. 4 is a bottom plan view showing the lever swung to open position; Fig. 5 is a front elevation of the guard lever support with the guard lever and spring removed, and Fig. 6 is a perspective view of the spring.

Similar reference numerals throughout the several figures indicate the same parts.

As the two sides of the mounting are duplicates of each other, only one is shown and the description applicable to both will

be given in the singular. In this view, 1 indicates the bridge, 2 the lens, 3 and 4 the clips and edge straps constituting the lens attaching portion, and 5 the connecting portion or table, preferably circular, upon which the finger-piece guard lever turns. In the present embodiment of the invention, the front edge of the table 5 is provided with an overhanging ledge or projection 6 extending from the lens attaching portion toward the bridge but terminating short of the latter, while rigidly attached to and depending centrally beneath the table is a cylindrical tube 7. The center of the table has formed therein a vertically extending bearing opening 8 that extends continuously through the tube 7.

The guard lever is indicated at 9 and comprises a forwardly extending operating portion or finger-piece 10 and the usual rearwardly extending looped adjustable portion 11 upon which is suitably mounted the guard or nose pad 12 that swings toward and from the gripping position against the nose under the influence of the lever. In the present instance, the pivot for the guard lever is carried thereby and consists of a pin 13 rigidly connected thereto and adapted to occupy the bearing opening 8 in the support from which it is removable in an axial direction when the guard is lifted for detachment.

The spring for actuating the guard lever and which normally presses the nose pad 12 inwardly for engagement with the nose, preferably comprises a flat spiral coil 14 composed of a ribbon or strip of flat material that encircles and is supported upon the tube 7 beneath the table or support 5 and to normally prevent its disengagement in a downward axial direction, the lower extremity of the tube 7 is provided with a laterally outstanding retaining flange 15 that engages the edge of an inner coil. In order to facilitate the application of the spring to its position on the tube, the said flange 15 preferably has a volute contour approximating that of the spring coils. It may be made necessary to slightly expand the latter while forcing them over the end of the tube, but in any event, the tension ultimately placed on the spring causes the coils to contract closely about the tube and to lock themselves beneath the flange. At its larger end, the flange terminates in a shoulder 16 with

which interlocks a lateral projection 17 on the inner end of the spring extending in a direction parallel with its axis, so that such inner end is thus secured to act against the support or stationary part of the mounting. The outer convolution of the spring terminates in a spring arm, the extremity of which engages and acts upon the rearward loop 11 of the guard lever that dips down to meet it, as shown in Fig. 3. At the point of engagement, a recess or saddle 19 is formed in the edge of the guard arm for the reception of the spring arm 18 and the latter is in this way prevented from lateral or vertical movement relatively to the guard and is securely interlocked therewith though readily disengaged therefrom in the horizontal plane of its spring movement.

In order to normally prevent axial movement of the guard lever 9 and its pivot 13 in the direction in which they are detached from the mounting, I provide two interlocking devices that act alternately during the turning movement of the guard lever so that when one is ineffective, the other will be effective. One such device consists of the ledge 6 on the table 5 in conjunction with a finger 19^a on the forward portion of the guard lever that co-operates therewith by running against the under surface thereof in all positions of the guard lever except when it is open or holding the nose engaging pad 12 away from the nose, as illustrated in Fig. 4. At this point, the finger 19^a has passed beyond the end of the ledge 6 and is in vertical alinement with an opening 20 (Fig. 1) between it and the bridge 1. At this point, the interlock described becomes ineffective to prevent axial movement of the lever, but in the meantime, the second interlock becomes effective. This second interlock comprises the lever engaging arm 18 of the spring acting in conjunction with an extension or abutment 21 on the support beneath which the spring arm swings when the finger-piece is in the extreme open position, as shown in Fig. 4. The said abutment engages the spring arm at a point so close to the latter's point of engagement with the guard lever that rigid support is given to the spring in holding the lever down and preventing its pivot from moving axially. Therefore, when it is required to remove the guard lever, the spring arm 18 must first be disengaged and then the lever moved to the extreme open position of Fig. 4 whereupon it is free to be raised, the finger 19^a thereon passing upward between the end of the ledge 6 and the bridge 1. The ready detachability of the spring 14 after its outer end is disengaged from the guard lever is obvious.

It will be observed that when the guard and its lever are in closed position against the nose, which is also the normal position of the mounting before it is applied to the

nose, the direct interlocking connection formed by the finger 19^a and the ledge 6 is always in engagement and hence there is no possibility of the parts becoming disarranged or loose while the mounting is in actual use. 70

This application contains the same disclosure as that of my prior abandoned application, Serial No. 4197, filed January 25, 1915. 75

I claim as my invention:

1. In an eyeglass mounting, the combination with a support and a finger-piece guard lever pivoted to turn thereon and detachable therefrom in an axial direction, of an interlocking connection between the lever and support for preventing such detaching movement, the interlock being effective during the greater part of the travel of the lever during its turning movement and ineffective at a point in its travel, and an actuating spring for the lever. 80

2. In an eyeglass mounting, the combination with a support, of a finger-piece guard lever pivoted to turn thereon and detachable therefrom in an axial direction when the lever is turned to open position, and means preventing such detachment of the lever while in other positions. 90

3. In an eyeglass mounting, the combination with a support and a finger-piece guard lever mounted to turn thereon, and detachable therefrom in an axial direction, one of said parts being provided with a bearing aperture and the other with a co-operating pivot member disengaged from the aperture when the lever is detached, of a finger on the lever normally interlocking with the support to prevent detaching movement of the lever but movable to an inoperative position permitting such detachment. 95

4. In an eyeglass mounting, the combination with a support embodying a table and a finger-piece guard lever having a pivotal bearing on the table from which it is detachable in an axial direction, of a laterally projecting ledge on the table and an interlocking part on the lever normally co-operating with the ledge to prevent detaching movement of the lever but movable with the latter to a position beyond the end of the ledge in which it permits such detachment. 110

5. In an eyeglass mounting, the combination with a support and a finger-piece guard lever having a pivotal bearing thereon from which it is detachable in an axial direction, of an interlocking connection between the lever and support for preventing detaching movement of the former throughout part of its arc of travel and a spring for actuating the lever also acting to interlock it with the support during the remainder of its arc of travel. 120

6. In an eyeglass mounting, the combination with a support and a finger-piece guard 130

lever having a pivotal bearing thereon from which it is detachable in an axial direction, of two devices for preventing axial movement of the lever arranged to act successively during the pivoting movement of the latter, one of said devices being adapted to be rendered inoperative.

7. In an eyeglass mounting, the combination with a support and a finger-piece guard 10 lever having a pivotal bearing thereon from which it is detachable in an axial direction, of two successively acting interlocking devices between the lever and support, one of which embodies a detachable spring for actuating the lever and is adapted to be rendered inoperative as a locking device.

8. In an eyeglass mounting, the combination with a support provided with an abutment and a finger-piece guard lever having 20 a pivotal bearing thereon from which it is detachable in an axial direction, of a direct

interlocking connection between the lever and support for preventing detaching movement of the former when in one position and a spring for actuating the lever embodying 25 an arm detachably engaging the same and adapted, when in engaging position, to cooperate with the abutment on the support and prevent detachment of the lever while the latter is in another position.

9. In an eyeglass mounting, the combination with a support and a finger-piece guard lever having a pivotal bearing thereon from which it is detachable in an axial direction, of a direct interlocking connection between 35 the lever and support for preventing detaching movement of the former when the guard is closed against the nose and a spring for actuating the lever and also acting to lock it against axial movement when the guard 40 is swung to open position.

PERCIVAL W. JONES.
